(57) **CLAIM**

The ornamental design for an infrared heater, as shown and described.

DESCRIPTION

Fig. 1 is a left elevation view of the infrared heater; Fig. 2 is a right elevation view thereof; Fig. 3 is a bottom plan view thereof; Fig. 4 is a rear elevation view thereof; Fig. 5 is a front elevation view thereof; Fig. 6 is a top perspective view thereof; Fig. 7 is a top plan view thereof; and Fig. 8 is a top plan view of the infrared heater provided in a different position relative to Fig. 1.

The broken lines shown in the drawings illustrate portions of the infrared heater which form no part of the claimed design.
